UNITED STATES PATENT OFFICE.

GEORGE F. BIBB, OF TROY, NEW YORK.

COMBINED COAL AND GAS RANGE.

1,348,078.

Specification of Letters Patent. Patented July 27, 1920.

Application filed March 13, 1920. Serial No. 365,567.

To all whom it may concern:

Be it known that I, GEORGE F. BIBB, a citizen of the United States, residing in Troy, New York, have invented certain Improvements in Combined Coal and Gas Ranges, of which the following is a specification.

My invention relates to certain improvements in the oven burner construction of a combined gas and coal range.

One object of the invention is to provide means for simultaneously closing the top and bottom of the burner chamber.

A further object of the invention is to provide sliding closures, which are connected together and which can be actuated from the front of the range.

A still further object of the invention is to provide means for preventing the turning of the gas valve when the burner chamber is closed and automatically releasing the valve when the closures are moved away from the opening.

In the accompanying drawings:

Figure 1 is a sectional view on the line 1—1, Fig. 2, showing the burner chamber open;

Fig. 2 is a sectional elevation of the lower portion of a range on the line 2—2, Fig. 1, showing the burner chamber open;

Fig. 3 is a sectional view, similar to Fig. 2, showing the entire oven and illustrating the burner chamber closed;

Fig. 4 is a sectional elevation on the line 4—4, Fig. 3; and

Fig. 5 is a detached perspective view of the burner chamber closures.

Referring to the drawings, 1 is the base of the range, in the present instance. 2 is the oven. 3 is the back plate of the range. 4 is the front plate. 5 is the top plate of the oven. 6 is the bottom plate of the oven and 7 is the bottom plate of the range formed integral with the base 1 and spaced from the oven bottom 6 to form a flue 8 for the passage of the products of combustion, which pass from an upper flue 9 to the top plate of the oven 5 and a side flue 10 at the side of the oven, as clearly shown in Fig. 4.

11 is the oven door of the usual construction and 12 is the hearth plate projecting from the range directly below the oven door. 13 is a casing located in the flue 8 between the bottom plate 7 of the range and the bottom plate 6 of the oven. This casing incloses the burner opening 14. Located in this open-

ing is a gas burner 15 shaped, in the present instance, as shown in Figs. 1 and 4. This burner has a neck 16 which extends to the front of the range and is enlarged at 17 to form an air intake chamber. Extending into this enlarged portion is a gas pipe 18 having a valve 19 and connected to the main gas supply pipe 20. The valve 19 has a handle 21.

22 is a sliding cover plate, which fits an opening 23 in the bottom plate 6 of the range, as shown in Fig. 3, and forms an upper closure for the burner opening 14. 24 is a sliding plate arranged to close an opening 25 in the bottom plate 7 of the range, as shown in Fig. 3. This plate closes the lower portion of the burner opening, as clearly shown in Fig. 3. Secured in position under the plate 7 is a flanged, recessed plate 26 having openings 27 for the admission of air, which are at the side, as shown, preventing the inrush of air. The plate is closed at the bottom. This arrangement provides sufficient air for the burner and the plate acts as a support and guide for the sliding plate 24.

In order that the plates 22 and 24 shall move in unison, I connect them, as illustrated in the drawings. The plate 22 is pivotally attached to a bar 27, at 28, and has a lug 29 fitting an opening 30 in the bar so that the plate while controlled by the bar is free to adjust itself in the opening 23. The connection 28 is sufficiently loose to allow the beveled end 31 of the plate to ride on an inclined surface 32 of the bottom plate 6, when the plate is withdrawn. The bar 27 passes through the front plate 4 of the range and has a curved outer end 33 forming a hand hold. This hand hold 33 is attached at its lower end to a bar 34 extending from the lower plate 24. This bar 34, in the present instance, is made integral with the plate 24, although, in some instances, it may be a separate piece bolted to the plate.

35 are two outlets for the products of combustion formed in the bottom plate 6 of the oven and they communicate with the bottom flue 8. These openings are closed by projecting portions 22^a of the cover plate 22, when the cover plate is over the burner and closing the burner passage. When the cover plate 105 is withdrawn, as in Fig. 1, the two passages 35 are open so as to allow for the escape of any products of combustion from the oven. 36 is the lower slide of the oven made in the form of a grating, in the present instance. 110

Attached to the under side of this slide is a deflector 37, which is above the burner opening.

In order to prevent the operation of the valve when the burner opening is closed, I provide a lever 38, which is pivoted at 39, and has an arm 40 having a projection 41 which, when turned in position, as denoted by dot and dash lines, Fig. 1, and full lines, Fig. 3, prevents the movement of the handle 21 so that it is impossible to turn on the gas. As soon as the slides 22 and 24 are withdrawn from the opening to the position illustrated in Figs. 1 and 2, then the lever 38 is moved clear of the handle 21 of the valve. The lever, in the present instance, has a long arm 42 slotted at 43. A pin 44 passes through this slot into a lug on the bar 27.

By the above construction, it will be seen that I am enabled to provide a combined gas and coal range with an oven burner located in the chamber below the oven bottom and to provide two sliding plates, one to close the upper portion of the burner chamber and the other to close the lower portion. These two plates are preferably connected so that they can be operated simultaneously. I provide a device for locking the gas valve when the burner chamber is closed, so as to prevent the accidental escape of gas into the burner opening when the range is used as a coal range.

I claim:

1. The combination in a combined coal and gas range, of an oven having a bottom plate therefor, the bottom plate of the range being spaced from the oven bottom plate so as to form a lower flue; a casing located between the two plates and forming the burner chamber; openings in the two plates connecting with the burner chamber; a burner in the chamber; two sliding plates, one adapted to close the opening in the bottom plate of the oven and the other arranged to close the opening below the burner; and means for connecting the two plates so that they will be moved in unison.

2. The combination in a combined coal and gas range, of an oven having a bottom plate therefor, the bottom plate of the range being spaced from the oven bottom plate to form a lower flue; a casing located between the two plates and forming the burner chamber; a burner in the chamber; two sliding plates, one adapted to close the opening in the bottom plate of the oven and the other arranged to close the opening below the burner; means for connecting the two plates so that they will be moved in unison; a valve for regulating the flow of gas to the burner; and lever mechanism connected to the plates so that when the plates are in position to close the burner opening, the valve will be locked against accidental movement.

3. The combination in a combined coal

and gas range, of an oven; a flue under the oven; a bottom plate for the oven and a bottom plate for the range located some distance from the oven bottom plate; a casing located between the two bottom plates and inclosing the burner chamber, said bottom plates having openings therein; a burner in the burner chamber; two sliding plates adapted to close the openings in the two bottom plates, one above and the other below the burner; a bar rigidly secured to the lower bottom plate; and a bar to which the first mentioned bar is connected and to which the upper plate is loosely connected so that when the upper plate is in position to close the opening, its upper surface is flush with the upper surface of the oven bottom plate.

4. The combination of a coal and gas range having an oven; a bottom plate for the oven; a bottom plate for the range located some distance below the oven bottom plate and forming a flue; a casing in the flue inclosing the burner chamber; openings in the two bottom plates; a burner in the burner chamber; a sliding plate arranged to close the lower opening; a sliding cover plate for the upper opening, said oven bottom being recessed to receive the upper cover plate so that when the plate closes the opening the upper surface of the plate will be flush with the top of the oven bottom plate; a bar extending to the front of the oven and connected to the lower sliding plate; a bolt loosely connecting the upper plate to the bar; and a lug on the cover plate extending into an opening in the bar, the outer edge of said cover plate being beveled so that when the plate is moved forward to expose the opening, the plate will ride upon the oven bottom plate.

5. The combination of a coal and gas range having an oven; a bottom plate for the oven; a bottom plate for the range located some distance from the oven bottom plate; a casing located between the two plates and forming a burner chamber; openings in the two plates; a burner in the opening; two slides arranged to close the openings; and an outlet in the bottom plate arranged to be closed by the upper slide when the burner chamber is closed.

6. The combination of a coal and gas range having an oven; a bottom plate for the oven and a bottom plate for the range located some distance below the oven bottom plate; a casing extending between the two bottom plates and forming a burner chamber; a burner therein; outlets in the bottom plate communicating with the flue between the two bottom plates; upper and lower sliding cover plates adapted to close the burner chamber; and extensions on the upper sliding plate arranged to close the outlets when the burner chamber is closed.

7. The combination of a coal and gas

range having an oven; a bottom plate for the oven having an opening therein; a bottom plate for the range located some distance below the oven bottom plate and having an opening therein in line with the opening in the oven bottom plate; a casing located between the two plates and forming a burner chamber; a burner therein; a flanged plate secured to the under side of the bottom plate and having side perforations, the plate be-

ing solid directly under the burner; a lower sliding plate; a perforated plate acting as a guide for the sliding plate; an upper sliding plate; bars for the plate extending to the front of the range and connected together; 15 and an outlet in the oven bottom plate at one side of the burner opening arranged to be closed by the upper sliding plate when the burner opening is closed.

GEORGE F. BIBB.
